UNITED STATES PATENT OFFICE.

DANL. B. HALL, OF BUCKSPORT, MAINE, ASSIGNOR TO HIMSELF AND
M. G. WILEY AND C. J. COBB, OF SAME PLACE.

IMPROVED RECUMBENT CHAIR.

Specification forming part of Letters Patent No. 58,343, dated September 25, 1866.

To all whom it may concern:

Be it known that I, DANIEL B. HALL, of Bucksport, in the county of Hancock and State of Maine, have invented a new and useful or Improved Recumbent Chair; and I do hereby declare the same to be fully described in the following specification and represented in the accompanying drawings, of which—

Figure 1 is a side elevation of it, with its back-frame elevated into its highest position. Fig. 2 is a longitudinal section of it, showing the back-frame as depressed to its lowest position. Fig. 3 is a top view of it.

In such drawings, A is a frame composed of two side pieces, *a a'*, connected by one or more cross pieces or bars, *b*, and having two rollers, *c d*, arranged within, as shown in Fig. 2, they being extended from one side piece to the other, and so applied to the two as to be capable of freely revolving on their axes. Each of such side pieces is curved on its upper edge to the arc of a circle, and is provided with two feet or legs, *e e*, to support it on a floor, the whole being as exhibited in the figures.

A movable back-frame, B, formed with arm-rests *f f*, and in other respects as represented, rests on the side pieces of the frame A, and is to be adapted to such frame in such manner as to be capable of being slid thereon from the position shown in Fig. 1 into that exhibited in Fig. 2, or vice versa. To the head-rest or cross-bar *g* of the back-frame one end of a sacking, C, is fastened, such sacking being carried partially around the front roller, *c*, and from thence to the back roller, *d*, to which the other end of the sacking is fastened.

A leg-rest, D, is supported by two metallic arms, *g' g'*, extending from the roller *c* at its two extremities, such arms being shown in Figs. 1 and 3. Each side piece of the back-frame B has one of two levers, *h h*, jointed to it, as shown at *i*. (See Fig. 2.) The said lever turns on a fulerum or pin, *k*, projecting from the inner side of one of the side pieces of the

supporting-frame A. The said pin or fulerum goes through a slot, *t*, made lengthwise in the lever. To each of the said levers an arm, *m*, is jointed, and extends toward and is jointed to the next adjacent arm *g'* of the leg-rest.

Another such arm is jointed to each lever *h*, and to one of two arms, *o o*, projecting from the ends of the roller *d*, such roller being not only for the purpose of giving support to the sacking, but for taking up the slack thereof during a forward movement of the chair-back frame.

Clamp-screws *p p*, or their mechanical equivalents, may be applied to the back-frame B, and so as to screw against the rail or side pieces of the supporting-frame A, the same being in order to hold the back of the chair at any desirable inclination within its range of motion. The back-frame may also be held to the supporting-frame by legs *q q*, extended from the back-frame into curved slots *r r*, made in each side piece of the frame A and parallel with the upper edges of the said side pieces.

On moving the said chair-back frame forward the leg-rest will be depressed, and the sacking will be wound on the back roller, *d*. A reverse motion of the back-frame will cause, through the action of the levers and arms, the back-frame to be depressed and the sacking to be unwound from the roller *d*.

I claim—

The above-described improved recumbent chair, consisting of the supporting-frame A, the movable back-frame B, the sacking C, the leg-rest, and the levers, arms, and rollers, as explained, or their mechanical equivalents, constructed, arranged, and applied substantially in manner and so as to operate together as hereinbefore specified.

DANIEL B. HALL.
